CLAIM

The ornamental design for a display screen with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a display screen with icon showing our new design;

FIG. 2 is a front view of a second embodiment of a display screen with icon showing our new design;

FIG. 3 is a front view of a third embodiment of a display screen with icon showing our new design;

FIG. 4 is a front view of a fourth embodiment of a display screen with icon showing our new design;

FIG. 5 is a front view of a fifth embodiment of a display screen with icon showing our new design;

FIG. 6 is a front view of a sixth embodiment of a display screen with icon showing our new design;

FIG. 7 is a front view of a seventh embodiment of a display screen with icon showing our new design;

FIG. 8 is a front view of an eighth embodiment of a display screen with icon showing our new design;

FIG. 9 is a front view of a ninth embodiment of a display screen with icon showing our new design; and,

FIG. 10 is a front view of a tenth embodiment of a display screen with icon showing our new design.

The broken lines illustrate the display screen and form no part of the claimed design. The design shown is not to be limited to any particular size and may be scaled larger or smaller.
